UNITED STATES PATENT OFFICE.

FREDERICK H. PERRY, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHOE MACHINE.

Application filed September 6, 1921, Serial No. 498,752. Renewed May 21, 1926.

This invention relates to machines for use in the manufacture of shoes and is illustrated herein as embodied in a heel seat fitting machine.

5 Before attaching wood heels to shoes it is usual to trim surplus stock from the peripheral portion of the heel seats of the soles of the shoe so that the edges of the soles will not be visible between the upper edges of the 10 heels and the material of the shoe uppers. This operation, which is called heel-seat fitting, was for a long time done entirely by hand, but more recently machines for performing the operation have been introduced. 15 It is necessary that the heel-seat fitting operation be performed with a considerable degree of accuracy for if insufficient stock is removed the joint between the edge of the heel and the shoe upper will not be tight, 20 and if too much stock is removed the bearing of the heel upon the sole of the shoe will not be solid. As long as heel-seat fitting was performed by hand this was entirely a matter for the skill and judgment of the 25 individual workman, but now that heel-seat fitting is being done by machinery it has become important to provide mechanical means for insuring such an accurate control of the heel-seat fitting machine organization 30 and the presentation of the work thereto as will insure that each shoe is trimmed to fit the particular size of heel which is to be attached to it.

It is accordingly an object of the present 35 invention to provide a heel-seat fitting machine organization having improved mechanism for controlling the dimensions to which the heel-seat portions of the soles operated upon are trimmed. With this object in 40 view, a feature of the invention comprises means for positioning a shoe during the performance of the heel-seat fitting operation and holding it stationary, a measuring device operable to measure a dimension of the 45 heel which is to be attached to the shoe or a heel like the heel which is to be attached to the shoe, and connections from the shoe-positioning means to the measuring means operating to cause the dimensions to which 50 the heel-seat of the sole of a shoe is trimmed to correspond to those of the heel measured.

Thus the heel acts as a templet or pattern to control the trimming or heel-seat fitting operation.

In the illustrated construction, a heel seat 55 fitting machine is shown provided with a support for a loose heel, a gage member readily and manually movable to engage the heel, and connections from the gage member automatically to control the operation of trimming and positioning instrumentalities of the machine to fit the heel seat of a shoe for the attachment of the heel which is being used as a templet or for another heel like that one. Thus each shoe is separately fitted for its heel, without loss of time and yet with entire accuracy.

Further objects of the invention are to overcome a tendency of the sole to buckle by frictionally wiping it rearwardly against 70 the push of the trimming knife, and to steady the work by means of the heel-breast knife while the edge knife makes its cut. These and other objects, and various improvements and specific novel constructions and combinations of parts, will be apparent from the following description of the illustrative machine shown in the accompanying drawings, in which:

Fig. 1 is a side elevation of the machine; 80
Fig. 2 is a perspective of the principal parts;

Fig. 3 is a top plan view of the heel support, the gage, and the sole supporting plates; and

Fig. 4 is a perspective of the counter-engaging member which determines the position of the shoes.

The herein disclosed novel method in the practice of which an unattached heel spaced 90 a substantial distance from the sole of a shoe is used to control the extent of an operation upon the shoe is not claimed herein since it forms the subject-matter of my co-pending application Serial No. 592,865, filed 95 October 6, 1922.

The illustrated machine, which is of the general type disclosed in Letters Patent of the United States No. 1,307,285, granted June 17, 1919, on an application of S. J. 100 Wentworth and F. H. Perry, is provided with a drive shaft 10 rotated one revolution

at a time by belt 12 acting through a one-revolution clutch controlled by a suitable treadle. Cams on shaft 10 operate the various parts of the machine according to a predetermined cycle. A lasted shoe is presented to the machine on a support 14 (or a shoe off the last may be presented thereto on a support of the type shown in the above identified patent). This support is clamped in operative position by a pawl 16, co-operating with a ratchet 18, and arranged to be released by pulling a hand-lever 20.

Plates 30 are spread apart against the resistance of spring 32, by depressing a suitable treadle, when a shoe is presented to the machine, and when the treadle is released they are yieldingly pressed toward one another, into the rand crease of the shoe, and act to support the margin of the sole. These plates are pivoted on a slide or head 34, which carries a cam roll 36 operated by a spiral cam 38, turned by means of a handle 40 which is held in adjusted position by allowing a spring pin to seat in one of a series of holes 42.

The operative position of support 14 is determined by engagement of the counter of a shoe thereon with a gage 31, shown in Figs. 2, 3 and 4. In the patented machine the corresponding gage is mounted directly on the slide corresponding to slide 34. For a purpose hereinafter explained, I have improved this construction by mounting counter gage 31 on a supplementary slide as shown in Fig. 4, arranged for adjustment longitudinally of slide 34 by turning two adjusting screws 33, one of which is shown in that figure.

The central portion of the heel seat of a sole supported by plates 30 is depressed by a matrix roll 44, journaled in the forked end of a lever 46, and the waste marginal portion of the sole which remains above plates 30, is severed to form a U-shaped flap by a reciprocating knife 48 which follows closely after the forward motion of the matrix roll. The U-shaped flap so formed is cut off at the breast line by reciprocating knives 50. The initial position of matrix roll 44 is adjusted simultaneously with plates 30 and gage 31, and during the cycle of the machine the roll is picked up by the mechanism for reciprocating knife 48, and carried forward from this variable initial position to a uniform forward position such that knife 48 cuts forwardly to the breast line, to co-operate with knives 50 in making angularly-related cuts which remove the waste marginal stock.

All of the foregoing parts, and the actuating mechanism therefor, may operate, and are illustrated as operating, substantially like the corresponding parts described in the above-identified patent, and no extended description is here deemed necessary. Certain

of these parts, however, are illustrated as improved in accordance with the present invention, and the nature of these improvements is hereinafter described in detail.

In order to provide for quickly setting slide 34, and therefore gage 31 and matrix roll 44, according to the particular heel for which a shoe is being fitted, a support 60 is provided on the frame of the machine, with an abutment 62 in alignment with the breast-line position determined by knives 50. To co-operate therewith, a gage or feeler 64 is mounted on slide 34 in alignment with the rear end of the heel of a shoe positioned by gage 31. In operating upon styles of shoes in which the rear end of the counter is in alignment with the rear edge of the heel, abutment 62 and gage 31 will be set in substantial alignment. In other styles, the position of gage 31 is so adjusted that the breast line of a shoe positioned thereby will be in alignment with the breast line of a heel engaged by abutment 62.

By this arrangement, when a heel H is placed on support 60 in engagement with abutment 62 and gage 64 is moved against the opposite side of the heel by setting slide 34 by means of handle 40, and when a jacked shoe on support 14 is swung back as far as permitted by engagement of gage 31 with the counter, the breast-line position determined by the junction of the cuts made by knives 48 and 50 is automatically set to fit the sole for the particular heel being used as a pattern. Thus the heel is made to serve as a pattern or templet and the shoe is trimmed to fit it.

Some difficulty has been experienced in trimming shoes having soles of comparatively flexible leather, in that such soles tend to buckle under the forward push of knife 48 and roll 44. To offset this, teeth 70 are provided on plates 30, to hold the soles against slipping, and teeth 72 are cut on the ends of roll 44, to force the roll to rotate at the angular speed determined by rolling engagement of the teeth with the soles. As the center matrix portion 74 of the roll is of materially greater diameter than toothed portions 72, the angular speed so determined is sufficient to give matrix portion 74 a peripheral speed in excess of what would give mere rolling engagement with the work, thus wiping the work rearwardly and offsetting the tendency to buckle.

I prefer to insure rotation of roll 44 at the desired speed by mounting a pinion 76 on one end thereof, of a diameter equal to portions 72. This pinion engages a rack 78 secured at one end to slide 34 and supported at the other end by a hanger 80 on arm 46.

To co-operate with the roll 44 in holding a sole, knives 50 are brought into engagement with the sole during the forward movement of knife 48 and roll 44. Then the

- knives 50 are raised while roll 44 advances thereunder and withdraws, during the completion of the cuts made by knife 48, and finally knives 50 are again brought down to 5 cut away the waste stock. This may be done by an appropriate design of cam 82, which acts through lever 84, link 86, and slide 88, to provide this double reciprocation of knives 50.
- 10 I prefer to cause a corresponding double reciprocation of knife 48 and roll 44, so that knives 50 may remain in engagement with the sole as long as possible, knife 48 and roll 44 pausing while knives 50 are 15 raised out of the way. This is done by an appropriate design of cam 90, which operates through lever 92, link 94, and rack 96, to reciprocate the slide which operates knife 48 and matrix roll 44.
- 20 In operation, a shoe is placed on support 14 and the corresponding heel on support 60, handle 40 is turned until gage 64 engages the heel, support 14 is swung back as far as gage 31 permits and until plates 30 25 seat in the rand crease, and the one-revolution clutch is tripped; whereupon the shoe is trimmed to fit the heel on support 60.
- When shoes such as turn shoes having sewed heel seats are to be operated upon, 30 gage 31 is not really necessary, as the plates 30 may be relied upon definitely to position the shoes. This will be apparent when it is considered that the stitching around the heel-seat will provide a definite abutment to 35 receive the edges of the plates 30. Many welt and McKay shoes, on the other hand, which are to receive wood heels, have the heel-seat portions of their soles secured at the time the heel-seat fitting operation is 40 performed only by a few tacks which cannot be relied upon to co-operate with the crease plates to position the shoe. When operating upon shoes of this kind a back gage, such as gage 31, which contacts with the counter 45 portion of the shoe at the position of the back seam will provide for the necessary accurate positioning of the shoe.
- While I have described my invention in connection with a machine of the type shown 50 in the Wentworth and Perry patent, it is not my intention to limit its scope thereby, or otherwise than by the terms of the appended claims.
- Having described my invention, what I 55 claim as new and desire to secure by Letters Patent of the United States is:—
1. A machine for operating on shoes having, in combination, means for supporting a shoe in a stationary position, means to prepare a shoe thus positioned for the attachment of a heel, a gage arranged to measure the heel which is to be attached to the shoe or a heel like that heel, and means controlled by said gage for controlling the preparation 60 of the shoe.
  2. A heel-seat fitting machine having, in combination, means for supporting a shoe in a stationary position, positioning means arranged to control the position of a shoe thus supported, means to trim surplus material 70 from the heel-seat of said shoe to fit the shoe for the attachment of a heel, a measuring device operable to measure the heel which is to be attached to the shoe or another heel like that heel, and connections from the measuring device to the positioning means to control the trimming operation in accordance with the size of the heel measured. 75
  3. A heel-seat fitting machine having, in combination, a plurality of crease plates arranged to enter the rand crease of a shoe and to support the peripheral portion of the heel-seat of the sole thereof, means for trimming surplus material from the peripheral portion of the heel-seat of the sole of a shoe thus positioned, means for measuring the heel which is to be attached to the shoe or another heel like that heel, and means connected to said measuring means for controlling the dimensions to which the heel-seat of the sole of the shoe is trimmed. 80
  4. A heel-seat fitting machine comprising a knife traveling lengthwise of the sole of the shoe operated upon through an unvarying path, means for presenting a shoe thereto to cause the knife to trim surplus material from the peripheral portion of the heel-seat of the sole of a shoe, means for measuring the heel which is to be attached to the shoe or another heel like that heel, and means controlled by said measuring means to control the position of the shoe during the trimming operation whereby the dimensions to which the heel-seat of the sole of the shoe is trimmed correspond with the dimensions 90 of the heel measured. 95
  5. A heel-seat fitting machine having, in combination, a plurality of crease plates arranged to enter the rand crease of a shoe to be operated upon, a cutter arranged to trim surplus material from the peripheral portion of the heel-seat of the sole of a shoe thus positioned, a knife for making a heel breast receiving cut at the forward end of the heel-seat of the sole of a shoe, means for measuring the heel which is to be attached to the shoe or a heel like that heel, and means controlled by said measuring means to position the breast cut and the forward extent of the trimming cut in accordance with the length 100 of the heel measured. 110
  6. A heel-seat fitting machine having, in combination, a knife movable lengthwise of the sole of a shoe to trim surplus material from the heel-seat portion of the sole thereof, means for measuring the heel which is to be attached to the shoe or a heel like that heel, and means controlled by said measuring means to determine the extent of the trimming operation, so that the heel-seat of 125 130

- the sole of the shoe will be trimmed to fit the heel measured.
7. A heel-seat fitting machine having in combination, means for trimming surplus material from the heel-seat portion of the sole of a shoe, a plurality of crease plates movable into the rand crease of the shoe to be trimmed and arranged to position the shoe in adjustable relation to the path of movement of the trimming means, a gage member movable into engagement with the heel to be attached to the shoe or a heel like that heel to measure said heel, and a connection between said gage member and said crease plates to cause the crease plates to move relatively to the path of movement of the trimming means as the gage is moved to measure the heel.
8. A heel-seat fitting machine having, in combination, a trimming device for removing surplus material from the periphery of the heel-seat portion of the sole of a shoe presented thereto, a support for a heel, a heel gage member movable relatively to a heel on the support into engagement with said heel to be thereby positioned in accordance with the length of said heel, a work gage arranged to control the position of a shoe in the machine, and connections between the two gages whereby the work gage is moved to control the position of the work in the machine so that the shoe will be trimmed to fit the heel engaged by the heel gage member or a heel like that heel.
9. A heel-seat fitting machine having, in combination, a work support, means for trimming surplus material from the periphery of the heel-seat portion of the sole of a shoe carried thereby, a support for a heel, a heel gage member movable relatively to a heel on the support to be thereby positioned in accordance with the length of said heel, a work gage arranged to control the position of the shoe in the machine, and connections between the two gages whereby the work gage is moved to control the position of the work support so that the shoe will be trimmed to fit the heel engaged by the heel gage member or a heel like that heel.
10. A machine for use in making shoes comprising, in combination, a knife to split the sole of a shoe to cut a flap loose therefrom, a device to determine the relative positions of a sole and the knife to control the length of the flap, and pattern-controlled means by which said device may be adjusted to change the length of flap cut thereby.
11. A machine for use in making shoes comprising, in combination, positioning and operating means to prepare a part of a shoe, a horizontal support spaced laterally therefrom on which a pattern may be laid, a member movable across the support to engage said pattern, and a connection to control the relative positions of the positioning and operating means according to the position of said member.
12. A machine for use in making shoes comprising, in combination, a cutter to remove a U-shaped piece of waste from about the heel end of the sole of a shoe, a separate knife to cut a shoulder at the heel-breast line, and gaging means controlled by a heel to determine the length of the U-shaped piece and the position of the heel-breast cut.
13. A machine of the type having a knife reciprocable perpendicularly against the sole of a shoe to determine the heel-breast line and comprising, in combination, means to present a shoe to the knife, a support beside the knife having an abutment arranged to engage the breast of a loose pattern and position the breast of the pattern in predetermined relation to the knife, and a member movable into engagement with the back of a pattern on the support and so connected to said shoe presenting means as to cause the shoe to be presented with the rear end of the heel seat in a corresponding relation to said member.
14. A heel-seat fitting machine of the type which has plates to support the edges of the rear end of the sole of a shoe, a gage to position the shoe, a matrix roll to depress the center of the sole below the plates, a knife reciprocated across the plates to cut off the part of the sole projecting above the plates in a U-shaped flap, and a knife moving against the sole at the heel-breast line to cut off the U-shaped flap so made, and comprising, in combination, a support for a loose heel beside the plates, an abutment thereon in predetermined relation to the heel-breast knife to engage the breast of a heel on the support, an abutment connected to the gage in predetermined relation thereto, and connections to move the abutment against the rear side of the heel and arranged thereby to move the gage to fix the rear end of the heel seat at a distance from the breast cut equal to the length of the heel.
15. In a machine of the class described, means for trimming the heel seats of shoes to prepare the heel seats for the reception of heels, a measuring device including a support for a heel, a gage part to engage one edge of the seat of a heel on the support, a second gage part to engage the opposite edge of the seat of the heel, means to move one of said parts toward the other to measure the seat of the heel, a cutting knife for severing the material from the heel seat at the breast line, and means to determine the cutting point of said knife controlled by the movement of the movable gage part.
16. A heel seat fitting machine comprising, in combination, means for supporting a shoe in a stationary position, a cutter arranged to trim surplus material from the peripheral portion of the heel seat of the sole

of a shoe thus supported, means relatively to adjust said supporting means and said cutter to vary the size of the heel seat formed thereby, and means to engage opposite sides of a heel to measure its size and connected with said adjusting means to determine the proper adjustment of said means.

17. A heel seat fitting machine comprising, in combination, a plurality of crease plates arranged to enter the rand crease of a shoe and support the periphery of an outsole attached thereto, a trimming device for removing waste material from a sole supported thereby to fit the shoe for the addition of a wood heel, a support for a loose heel, a gage member movable across the support into engagement with a heel thereon and thereby positioned in accordance with the length of the heel, a work gage arranged to position the shoe in the machine, and connections between the two gages whereby the work gage is moved to set the machine to fit different shoes to receive different heels placed on the support.

18. A heel seat fitting machine comprising, in combination, a plurality of crease plates arranged to enter the rand crease of a shoe and support the periphery of an outsole attached thereto, a trimming device movable with respect to the plates to remove waste material from an outsole supported thereby to fit the shoe for the attachment of a wood heel, a back gage arranged for engagement with the rear portion of the shoe, and movable to determine the length of the part of the sole operated on by the trimming device, a member movable into engagement with a wood heel to determine the length of its heel seat surface, and means for connecting and simultaneously moving said heel engaging member and the back gage to set the machine to trim different shoes differently to prepare them for the addition of different heels engaged by said member.

19. A heel seat fitting machine comprising, in combination, a shoe support, a plurality of crease plates arranged to enter the rand crease of a shoe on said support, to support substantially the entire peripheral portion of the heel-seat of the sole of the shoe, means for trimming the periphery of the sole of a shoe thus supported to fit it for the attachment of a wood heel, a mechanically-operated knife to form a shoulder at the heel breast line, a device for limiting the extent of the part of the sole operated on by said trimming means and for varying the relative positions of the shoe and the heel breast knife to determine the position of the heel breast line, and mechanism for engaging a wood heel and measuring the length of its seat surface and for setting said device according to the length so measured in order to adjust the machine to trim different shoes

differently to fit them for the addition of different heels measured by said mechanism.

20. A machine for operating on shoes comprising, in combination, supporting means for the edges of the sole of a shoe, and a matrix roll to depress the center of the sole below the supporting means and simultaneously to urge the sole rearwardly.

21. A machine for use in making shoes comprising, in combination, a tool operating on a piece of stock, a roller presser foot having a roughened surface to hold the stock against the tool, and means to rotate the roller foot to wipe it against the stock to urge the stock toward the tool to prevent buckling.

22. A machine for use in making shoes comprising, in combination, a work-support, a roller engaging work thereon, and means relatively to move the support and the roller to rotate the roller about its axis in engagement with the work and to accelerate its peripheral speed frictionally to urge the work in a direction to offset the tendency to buckle caused by the rolling friction of the roller on the work.

23. A machine for operating on soles comprising, in combination, a knife to make a cut longitudinally of the sole of a shoe, a matrix roll engaging the sole ahead of the knife, means to move the knife and roll relatively to the sole, and means to rotate the roll frictionally to urge the sole in a direction opposite to the cut to prevent buckling.

24. A machine for operating on soles comprising, in combination, a cutter and a support relatively movable to make a longitudinal cut in a sole on the support, a roll having a pinion on one end and an enlarged central portion to engage the sole ahead of the cutter, and a rack fixed relatively to the support to engage the pinion and rotate the roll so that the enlarged portion will have a frictional wiping action to offset the tendency of the sole to buckle ahead of the cutter.

25. A heel-seat fitting machine comprising, in combination, a support for the edges of a sole, a matrix roll to depress the central portion of the sole below the support, a knife behind the roll to cut off the portion of the sole above the support, means relatively to move the support and the knife and roll, and means to rotate the roll at a peripheral speed higher than the linear speed of the sole relatively to the knife and roll in such a manner as to wipe the sole toward the knife to offset the tendency to buckle.

26. A machine for operating on soles comprising, in combination, a support for a sole, a tool to operate progressively and longitudinally on the sole, and a member movable against the free surface of the sole

and remaining stationary in engagement therewith during the operation of said tool to prevent displacement by said tool.

27. A machine for operating on soles comprising, in combination, a support for a sole, a tool to operate progressively and longitudinally on the sole, and a second tool movable against the free surface of the sole to prevent displacement thereof and thereafter operable to co-operate with the first tool to prepare the sole for a succeeding operation.

28. A trimming machine comprising, in combination, cooperating knives movable to make angularly-related cuts in a piece of stock to remove the portion outlined thereby, and mechanism to move one of the knives into engagement with the stock to hold it while the second knife makes its cut and thereafter to further move the knife to make a cut in the stock to join the cut made by the second knife.

29. A heel-seat fitting machine comprising, in combination, a knife for severing a

flap of waste about the heel seat of a sole, a co-operating knife to cut off the flap at 25 the heel-breast line, and mechanism to move the second knife against a sole during the first portion of the action of the first knife and then to raise it out of the way as the first knife approaches the breast line and 30 thereafter to lower it again to cut off the flap severed by the first knife.

30. A heel-seat fitting machine comprising, in combination, a knife to cut the surplus material from about the edge of a sole, 35 a matrix roll ahead of the knife, and a knife moved against the breast line to hold the sole until the approach of the matrix roll, then moved up out of the way to allow the roll to pass thereunder and be withdrawn, 40 and then moved against the sole again to make the breast line cut.

In testimony whereof I have signed my name to this specification.

FREDERICK H. PERRY.
